[57] CLAIM

The ornamental design for a clock face, as shown and described.

DESCRIPTION

FIG. 1 is a front and bottom-left perspective view of a clock face showing my new design;

FIG. 2 is a front elevational view thereof;

FIG. 3 is a bottom plan view thereof, the top plan view being a mirror image;

FIG. 4 is right side elevational view, the left side being a mirror image;

FIG. 5 is a rear elevational view thereof, the dial plate having been omitted for ease of illustration; and

FIG. 6 is a cross-sectional view as taken from line 6—6 of FIG. 2.

FIG. 1

FIG. 2

FIG. 3

FIG. 4

FIG. 6

FIG. 5
